W. C. F. ZIMMERMAN, JR. & H. L. ZIMMERMAN.
STUMP PULLING APPARATUS.
APPLICATION FILED OCT. 24, 1914.

1,280,356.

Patented Oct. 1, 1918.

UNITED STATES PATENT OFFICE.

WILLIAM C. F. ZIMMERMAN, JR., AND HENRY L. ZIMMERMAN, OF LONE TREE, IOWA.

STUMP-PULLING APPARATUS.

1,280,356.

Specification of Letters Patent.

Patented Oct. 1, 1918.

Application filed October 24, 1914. Serial No. 868,472.

To all whom it may concern:

Be it known that we, WILLIAM C. F. ZIMMERMAN, Jr., and HENRY L. ZIMMERMAN, citizens of the United States, residing at 5 Lone Tree, in the county of Johnson and State of Iowa, have invented certain new and useful Improvements in Stump-Pulling Apparatus; and we do hereby declare the following to be a full, clear, and exact description of the invention, such as will enable others skilled in the art to which it appertains to make and use the same.

This invention relates to improvements in stump pulling apparatus, and more particularly to the cable winding drum, its frame and attachments.

An object in view is the provision of simple and efficient means for quickly and easily connecting and disconnecting a sweep- 20 actuated shaft with a drum.

A further object is the provision of means for sustaining a drum ratchet-engaging pawl either in or out of operative position.

With these and further objects in view, 25 as will in part be hereinafter stated and in part become apparent, the invention comprises certain novel constructions, combinations and arrangements of parts as will be hereinafter specified and claimed.

30 In the accompanying drawing,—

Figure 1 is a view in side elevation of an apparatus embodying the features of the present invention.

Fig. 2 is a longitudinal, vertical, central 35 section therethrough.

Fig. 3 is a fragmentary top plan, parts being seen in horizontal section, the section being taken on the plane indicated by line 3—3 of Fig. 2.

40 Fig. 4 is a detail perspective view of the manually actuated spindle and one of the pawls which coöperates therewith detached for clearness of disclosure.

Fig. 5 is a detail perspective view of the 45 pawl detached.

Figs. 6 and 7 are fragmentary, detail, vertical sectional views showing the pawl in elevation, respectively, in its engaging and disengaged positions.

50 Fig. 8 is a fragmentary section taken on the plane of line 7—7 of Fig. 2.

Fig. 9 is a detail side elevation of the actuating and locking means for the clutch.

Referring to the drawing by numerals, 1 55 indicates an ordinary stump puller drum frame having the hook 2 for engaging an

anchoring cable. The upper portion of the frame is formed with an annular opening 3 and the lower portion of the frame is formed with an axially aligned annular opening 4. 60 A cylinder 5 is snugly fitted within the opening 3 and is provided with a finger 6 underhanging the under face of the upper portion of the frame 1, the finger being introduced through a radial notch 7 formed in the upper portion of frame 1 and opening into the area 3. Though the finger 6 travels and, therefore, comes into register with notch 7 once in every revolution of cylinder 5 the time of perfect registration is only instantaneous, and at all other times the finger affords a means of preventing the cylinder 5 from rising in the frame. A tubular shaft 8 depends from cylinder 5 and extends downwardly through the aperture 4 in the lower 70 portion of the frame, finding bearing therein. A hollow drum 9 surrounds the shaft 8 and is formed with a rectangular aperture in which fits the squared portion 10 of shaft 8. The upper end of the drum is provided 75 with a flange whose outer edge is formed into a ratchet 11, and the lower end of the drum is provided with a flange 12 which flares downward so as to be constantly clear of the cable being reefed in or paid out, 80 and also providing a clearance between inner portions of the flange and adjacent portions of frame 1 so to accommodate the inner enlarged end of a cable secured in the eyelet 13 formed in the flange, and at the 85 same time permit the drum to be moved laterally into and out of the frame without interference of such cable end with the frame when that portion of the flange is moved through the frame. The end of the cable 90 is also thus prevented from presenting a protuberance liable to strike part of a crate or casing in which the machine may be shipped or stored.

The cylinder 5 is hollow and its inner surface is formed with a series of abrupt shoulders 14, 14, and inclined walls leading from the outer end of each shoulder 14 in a curved line to the inner end of the next adjacent shoulder 14 so as to produce an internal 100 ratchet wheel with which coöperates pawls 15, 15. Spaced above the upper portion of frame 1 is a sweep receiving casing or box 16 having depending lugs 17, 17, resting upon the frame adjacent the end portions of the box. Centrally of and preferably formed 105 integral with the bottom of the box is ar-

ranged a tubular depending shaft 18 which is nested within shaft 8 and arranged concentric therewith. Spaced below the upper end of shaft 18 and approximately in the 5 horizontal plane of the lower end of cylinder 5, the shaft 8 is formed with radial ears 19, 19, one for each pawl 15, and the pawls are sustained pivotally by pintles 20 engaging said ears at their lower ends and the bottom 10 of box 16 at their upper ends. Shaft 18 is provided with radial, axially extended flanges or beads 21, one such flange being provided for each pawl 15, and each flange being formed with a longitudinal groove in 15 its side face, which groove is transversely arcuate or curved to correspond with the rounded portion of the end of the respective engaging pawl 15 whereby the twisting or rotary stress is delivered from shaft 18 20 through the flanges, rather than through pintles 20 to pawls 15, as will hereinafter more clearly appear. Each pawl 15 is formed with a substantially radially inwardly extending finger 22 which projects 25 through an aperture 23 in the shaft 18, each aperture 23 being enlarged inwardly for accommodating a swinging movement of the finger 22 on the pintle 20 as an axis. A cylindrical spindle 24 extends into and 30 snugly fits the upper end portion of shaft 18 and projects upwardly through the bottom of box 16, the upper end of the spindle being formed with a disk or head 25. The spindle 24 is formed with longitudinal 35 grooves 26 into which the fingers 22 extend, each groove being transversely curved and describing the greater part of a circle, as best seen in Fig. 3, so that the respective engaged finger is free to have the required 40 movement when the spindle is rotated. The bottom of box 16 has its intermediate portion depressed, and forming an annular portion 16' of the same diameter and axially aligned with cylinder 5, as clearly seen in Fig. 45 1. This depression is sufficient for causing the upper surface of disk 25 to lie below the main portion of the bottom of box 16 so that the sweep which in operation rests within the box 16 does not rest upon disk 25. Spindle 24 is formed at its upper end with an aperture 27 which is engaged by an operating bar 28 forming a lever or handle for rotating the spindle 24 and extending through a slot 29 formed in the annular portion 16'. 50 55 Thus, in operation, when the lever 28 is swung in one direction the spindle 24 will be rotated for swinging the fingers 22 in a direction for drawing in the pawls 15 to the position indicated in full lines in Fig. 3, 60 whereupon the drum 9, shaft 8, and cylinder 5 will be free to revolve independently of the box 16 and its connected parts, as when cable is being paid out from the drum. When it is desired for the drum to be rotated by the sweep engaging box 16, lever 28

is swung to its other extreme which rotates spindle 24 and shifts the fingers 22 and thereby swings pawls 15 outwardly to the position indicated in dotted lines in Fig. 3 with the free ends of the pawls engaging the internal ratchet of cylinder 5, whereupon rotation of box 16 will impart similar movement to cylinder 5 and drum 9. 70

To prevent reverse rotation of drum 9 while its cable is under tension, a pawl 30 75 is disposed to engage ratchet 11, the pawl being pivotally mounted between ears 31 standing from the upper portion of frame 1 at opposite sides of a notch 32 formed in said portion of the frame, the pawl being disposed to swing within the notch. The lower or free end portion of the pawl is adapted to swing into and out of engagement with the teeth of ratchet 11. To facilitate reverse rotation of drum 9, means are 80 provided for locking the pawl in a raised position out of the path of the ratchet 11, and the means to this end consists of a substantially J-shaped bolt 33 having its body extending through the body of the pawl 30 90 and its shank extending alongside the pawl and adapted to engage either an aperture 34 or an aperture 35. A spring 36 surrounds the body of the bolt at one side of pawl 30 and is tensioned to press the bolt in a direction for causing the shank to remain in either of the given positions with the short end portion in aperture 34 or in aperture 35. When the pawl is to operate normally, the shank of the bolt is disposed with its short 100 end portion in aperture 34, and the pawl is then free to swing to the position indicated in Fig. 6, but when it is desired to allow the drum 9 to revolve freely the bolt is adjusted to the position indicated in Fig. 7 where the 105 short end engages the aperture 35, and, in this position, the bolt rests against the contiguous edge of frame 1 and supports the pawl clear of ratchet 11. 95

In operation, the hook 2 is anchored and 110 the cable which is wound about drum 9 is connected to the stump to be extracted. The box 16 is revolved by a draft animal actuated sweep or other appropriate means, the pawls 15 having previously been adjusted to position for engagement with the internal ratchet of cylinder 5, whereby the cylinder is revolved and the drum 9 likewise revolved so that the cable is hauled in, the pawl 30 serving to prevent return rotation in the event the stress on the box 16 is temporarily relaxed. This operation is continued until the stump is extracted, and then the pawl 30 is lifted and the bolt 33 120 adjusted to the position indicated in Fig. 7. 125 The cable is then detached from the extracted stump, moved to another stump and the operation repeated. In the course of moving the cable to a second stump, to avoid necessity for revolution of box 16 and its 130

connected parts, the lever 28 is moved for retracting pawls 15, and the drum 9 is thus left free for rotation.

To avoid accidental movement of pawls 15, particularly when the parts are out of gear, the pawls are designed to be locked in their respective clutched and unclutched positions by locking the lever 28 in either of the extremes of its movement, as by any appropriate detent such as a spring pressed bolt 28' carried by lever 28 and positioned to engage apertures 28" in box 16.

What we claim is:—

1. In stump pulling apparatus, the combination, with a frame, of a cylinder journaled therein and having an internal ratchet, a sweep support having a shaft extending into the ratchet, a spindle extending within the shaft of the sweep support, 15 a pawl carried by the shaft and having a finger engaging the spindle and adapted to be swung when the spindle is oscillated for swinging the pawl into and out of engagement with the ratchet, and a drum connected to be actuated by the cylinder.

2. In stump pulling apparatus, the combination, with a frame, of a cylinder journaled therein and having an internal ratchet, a sweep support having a shaft extending into the ratchet, a spindle in the shaft, said spindle being formed with a groove, a pawl within the cylinder and pivotally engaging the shaft and having a finger extending through the wall of the shaft 20 and into the groove of the spindle for enabling shifting of the pawl to and from engagement with the ratchet by rotary movement of the spindle, and a drum actuated by the cylinder.

3. In stump pulling apparatus, the com-

bination, with a frame, of a cylinder journaled therein, and having an internal ratchet, a sweep support having a shaft extending into the ratchet, a spindle in the shaft, said spindle being formed with a 45 groove, a pawl within the cylinder and pivotally engaging the shaft, and having a finger extending through the wall of the shaft and into the groove of the spindle for enabling shifting of the pawl to and from engagement with the ratchet by rotary movement of the spindle, a flange on the shaft disposed to receive the end thrust of the pawl, and a drum actuated by the cylinder. 50

4. In stump pulling apparatus, the combination, with a frame, of a cylinder journaled therein and having an internal ratchet, a sweep support having a shaft extending into the ratchet, a spindle in the shaft, said spindle being formed with a 55 groove, a pawl within the cylinder and pivotally engaging the shaft and having a finger extending through the wall of the shaft and into the groove of the spindle for enabling shifting of the pawl to and from engagement with the ratchet by rotary movement of the spindle, a flange on the shaft disposed to receive the end thrust of the pawl, the edge of the pawl contacting with the flange being transversely rounded and 60 the flange being correspondingly concaved, and a drum actuated by the cylinder. 65

In testimony whereof we affix our signatures in presence of two witnesses.
